5 ↔ 5A

Fig. 1

Fig. 2

Fig. 3

Fig. 4

FIG. 5

FIG. 6

FIG. 7

FIG. 1 is a front elevation of a light attracting insert electrocutor, the rear elevation of FIG. 1 being plain;

FIG. 2 is an elevation of the right-hand side of FIG. 1, the elevation of the left-hand side of FIG. 2 being opposite hand;

FIG. 3 is a sectional plan view taken along line 3—3 in FIG. 1;

FIG. 4 is a bottom view of FIG. 1, the top view being plain;

FIG. 5 is a vertical sectional view taken along line 5—5 in FIG. 1; the view taken along line 5A—5A in FIG. 1, being opposite-hand to FIG. 5;

FIG. 6 is a sectional view taken along line 6—6 in FIG. 1, and

FIG. 7 is an isometric view of the front grill of FIG. 1. The diagonal linings in FIGS. 1, 3, 5 and 6 denote mirrored light reflecting surfaces.

I claim:

The ornamental design for a light attracting insect electrocutor, substantially as shown and described.
